EXERCISE CONDITIONER APPARATUS

Dennis D. Windscheffel, 11811 Old River School Road,
Downey, Calif. 90241

Filed Oct. 13, 1969, Ser. No. 19,532

Term of patent 3½ years

Int. Cl. D21—03

U.S. Cl. D34—5

FIG. 1.

FIG. 2.

FIG. 3.

FIG. 4.

FIG. 1 is a side perspective view of an exercise conditioner apparatus showing my new design;

FIG. 2 is a side elevation thereof opposite that shown in FIG. 1;

FIG. 3 is a top plan view thereof; and

FIG. 4 is an end elevation thereof, both ends being the same.

I claim:

The ornamental design for an exercise conditioner apparatus, substantially as shown and described.
